US0D1102473S

(12) **United States Design Patent** (10) **Patent No.:** **US D1,102,473 S**
(45) **Date of Patent:** **** Nov. 18, 2025**

(54) **PORTION OF AN ELECTRONIC DEVICE DISPLAY SCREEN WITH GRAPHICAL USER INTERFACE**

(71) Applicant: **Truist Bank**, Charlotte, NC (US)

(72) Inventor: **April Wu**, Charlotte, NC (US)

(73) Assignee: **Truist Bank**, Charlotte, NC (US)

(**) Term: **15 Years**

(21) Appl. No.: **29/966,170**

(22) Filed: **Sep. 30, 2024**

(57) **CLAIM**

The ornamental design for a portion of an electronic device display screen with graphical user interface as shown and described.

DESCRIPTION

The sole FIGURE is a front view of a portion of an electronic device display screen with graphical user interface showing the claimed design.

The outer dash-dot-dash lines in the FIGURE show a portion of an electronic device display screen, and forms no part of the claimed design. The dash-dot lines in the FIGURE show portions of the graphical user interface that form no part of the claimed design.
